DESIGN FOR A DRESS

Fred Greenberg, New York, N. Y.

Application January 27, 1941, Serial No. 98,440

Term of patent 3½ years

To all whom it may concern:

Be it known that I, Fred Greenberg, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is the rear view of Fig. 1, and Fig. 3 is a fragmentary view of Figs. 1 and 2 when viewed downwards showing the raglan front and regulation armhole rear portion of Figs. 1 and 2.

I claim:

The ornamental design for a dress, substantially as shown.

FRED GREENBERG.
